UNITED STATES PATENT OFFICE.

LEE O. BISHOP, OF GREAT FALLS, MONTANA.

DESIGN FOR A FINGER-RING, BROOCH, OR SIMILAR ARTICLE.

49,533.

Specification for Design.

Patented Aug. 22, 1916.

Application filed May 27, 1916. Serial No. 100,399. Term of patent 7 years.

To all whom it may concern:

Be it known that I, LEE O. BISHOP, a citizen of the United States, residing at Great Falls, in the county of Cascade and State of Montana, have invented a new, original, and ornamental Design for a Finger-Ring, Brooch, or Similar Article, of which the following is a specification, reference being had to the accompanying drawing forming part thereof.

Figure 1 is a plan view of a finger ring illustrating my new design; Fig. 2 is a front elevation.

I claim:

The ornamental design for a finger ring, brooch or similar article as shown.

LEE O. BISHOP.

Witnesses:

ESTELLA M. BISHOP,
ANNA LYNCH.
